A. N. PAFF

APPARATUS FOR HOLDING AND DISPENSING ROLLS OF SHEET METAL

Filed Jan. 25, 1923

A. NORMAN PAFF INVENTOR.

BY Rickey, Slough + Watts

HIS ATTORNEYS

UNITED STATES PATENT OFFICE.

ALBERT NORMAN PAFF, OF BEAVER FALLS, PENNSYLVANIA.

APPARATUS FOR HOLDING AND DISPENSING ROLLS OF SHEET METAL.

Application filed January 25, 1923. Serial No. 614,756.

To all whom it may concern:

Be it known that I, ALBERT NORMAN PAFF, a citizen of the United States, residing at Beaver Falls, in the county of Beaver and State of Pennsylvania, have invented certain new and useful Improvements in Apparatus for Holding and Dispensing Rolls of Sheet Metal, of which the following is a full, clear, concise, and exact description 10 of my invention, such as will enable others skilled in the art to which it appertains to make and use the same.

This invention relates to an apparatus for holding and dispensing a roll of sheet 15 metal stripping.

The object of my invention is to provide a simple, inexpensive holder whereby a roll of material can be readily inserted and held in projected, elevated position, so that desired lengths thereof can be handily unrolled and cut off.

Another object of my invention resides in the mechanism for retaining a roll of metal stripping in elevated position in a holder to 25 prevent unrolling of its own accord.

It is a further object of my invention to simplify and improve the construction and operation of a device of this character, and effect the material reduction in the cost of 30 manufacture.

Another object of my invention consists in several novel features of construction and new combination of parts, hereinafter fully set forth and pointed out in the following 35 specification and claims.

Referring to the drawing, Fig. 1 represents a side elevation of the holder with a roll of sheet stripping supported therewith; Fig. 2 is a sectional view of the holder showing 40 the roll engaging the lower bearing, taken on line B—B of Fig. 1; Fig. 3 is a sectional view thru the holder illustrating the upper bearing roller engaging the roll of stripping, taken on line A—A of Fig. 1; and Fig. 4 is a fragmentary top plan view 45 of the tension arm in engagement with the roll.

The apparatus constituting my invention is designed primarily for use in stores where 50 it is desired to display a roll of strip brass, and also to secure the roll in elevated position, so that the salesman can readily unroll and cut off desired lengths therefrom. The casing is adapted to be nailed or screwed to 55 the wall, or a standard, so that it will be po-

sitioned several feet from the floor. It is obvious, however, that this invention can be used for holding rolls of strip metal of various types, and that the holder can be secured in various other suitable methods. 60

Referring in detail to the drawings, I provide a casing which is made up preferably as a unit from sheet metal, and which consists of a base member 10 adapted to be secured to a wall 11, and substantially parallel sides 11 65 projecting outwardly from the base member which receive a portion of the roll therebetween. A portion of the side members 11, near the bottom thereof, are pressed inwardly forming bearing members, or shoulders 12, against which the outer portion of a roll of strip material 13 engages. Angular slots 14 extend from the forward upper edges of the sides 11 and provide a bearing 70 to receive a shaft 15, upon which a bearing roller 16 is mounted intermediate of the walls. The shaft and roller are removable from the casing, and when removed, the roll of strip material is placed between the walls 11 so that the outer edge thereof rests against 75 the flanges 12. The roll is then pressed upwardly sufficiently to permit the shaft 15 and the roller 16 to be secured in position with the casing. When the roller is in such position the roll of material is dropped 80 down and allowed to rest upon the roller with its inner edge, and thus provide a lower bearing member and an upper roller bearing member which engage the outer and inner edges of the roll and hold it in projected 85 relation with the casing. 90

A curved tension arm 17 is hinged at 18, to the top portion of the base member of the casing, and projects forwardly above and beyond the side walls of the casing. A U-shaped member 18 is secured to the end of the tension arm by a bolt 19 and the sides of this member extend down adjacent the sides of the upper portion of the roll of strip material. A rubber strip 20 extends 100 around the end of the tension arm 17 and the U-shaped member 18 and is secured in position therewith by the bolt 19. A coil spring 21 is secured to the tension arm 17 and the base member 10, extending therebetween forwardly of the hinge 18. This spring creates tension against the arm 17 so that the end of the arm is pressed down 105 against the roll 13 to assist in holding it in a substantially stationary position and at the 110

same time preventing the roll from unwinding.

It is to be understood that a plurality of sides 11 could project from the base member 10 to provide holders for several rolls to be held side by side, if so desired.

This type of casing allows a roll of material to be readily inserted or removed from a holder, and permits the roll of metal tape 10 to be unrolled with a minimum amount of friction and effort due to the friction bearing roller 16.

Various changes in the details of construction can be made without departing 15 from the spirit and scope of my invention as described, and as set forth in the appended claims.

What I claim is:—

1. A holder for suspending a roll of strip 20 material comprising a casing having side members between which a portion of the roll of material extends, a pair of spaced bearing members secured intermediate the sides of said casing and located in different horizontal planes, one of said members bearing against the interior of the roll of material and the other of said members bearing against the exterior of the roll of material, and a tension arm adapted to engage the exterior of the roll of material adjacent the member bearing against the interior of the roll of material.

2. A holder for suspending a roll of strip 35 material comprising a casing having side members, a lower bearing member supported between the sides of said casing for engaging the outer portion of the roll of material, an upper bearing member between the sides of the said casing for engaging the inner portion of the roll of material forwardly of the lower bearing member, and a tension arm adapted to engage the outer portion of the roll forwardly of said upper bearing member.

3. A holder for supporting a roll of strip 50 material comprising a casing having substantially parallel sides adapted to enclose a portion of a roll of material, flanges extending inwardly from the sides of said casing to provide a lower bearing for engaging the outer portion of a roll of material, and an upper bearing member between the sides of said casing for engaging the inner portion of the roll of material forwardly of said flanges, and a tension arm adapted to engage the outer portion of the roll of material adjacent said upper bearing member.

4. A holder for suspending a roll of strip 60 material comprising a casing having substantially parallel sides adapted to enclose the rear portion of a roll of material, a lower bearing member between the sides of said casing for engaging the outer portion of the roll of material, and an upper roller bearing extending transversely between the

sides of said casing to engage the inner portion of the roll of material, said roller bearing being rotatable relative to the roll of material, and a tension arm adapted to engage the outer portion of the roll of material adjacent said upper bearing member.

5. A holder for a roll of strip material 70 comprising a casing having substantially parallel projecting sides adapted to receive a portion of the roll therebetween, said sides having aligned slots extending downwardly from their upper edges, a lower bearing member extending between the sides of said casing for supporting the outer portion of the roll, a removable roller supported by a shaft mounted in the slotted sides of said casing, said roller extending interiorly of the roll of material and being rotatable and removable independently of the roll of material, and a tension arm adapted to engage 80 the exterior of the roll of material adjacent said roller.

6. A holder for a roll of strip material 85 comprising a casing having substantially parallel projecting sides adapted to enclose a portion of the roll, a lower bearing member within the sides of said casing to engage the outer portion of the roll, an upper forward roller secured within the sides of said casing to engage and support the inner portion of the roll, and a tension arm pivoted to said casing above said bearings, and a coil spring secured to and between said arm and said casing to exert downward pressure against the roll.

7. A holder for a roll of strip material 90 comprising a casing having substantially parallel projecting sides adapted to enclose a portion of the roll, a lower bearing member within the sides of said casing to engage the outer portion of the roll, an upper forward roller secured within the sides of said casing to engage and support the inner portion of the roll, a pivoted tension arm 95 extending forwardly over said roll, and a U-shaped member secured to the end of said arm to extend over and engage the roll forwardly the said roller.

8. A holder for a roll of strip material 100 comprising a casing having substantially parallel projecting sides adapted to enclose a portion of the roll, a lower bearing member within the sides of said casing to engage the outer portion of the roll, an upper forward roller secured within the sides of said casing to engage and support the inner portion of the roll, a pivoted tension arm 105 extending forwardly over said roll, and a rubber cover secured to the end of said arm to engage the outer portion of the roll.

9. A roll holder comprising a casing including a base plate adapted to be secured to a wall and parallel sides projecting from the base plate, bearing members turned in and extending transversely of the sides of 110

20

said casing, a roller mounted above and forwardly of said bearing members between the sides of said casing, said bearing members and said roller respectively engaging the outer and inner surface of the portion 5 of the roll near the casing, and a pivoted spring operated tension arm for engaging the roll of material at a point beyond said roller.

25

10. 10. A holder for suspending a roll of strip material comprising a frame, a rotatable roller carried by said frame for engaging the inner portion of a roll of material, said roller having a rolling contact against the 15 roll of material, and a bearing carried by said frame in a plane beneath said roller for engaging the outer surface of a roll of material, and a tension arm engaging the

outer surface of the roll of material adjacent said roller.

11. A holder comprising a frame, adapted to receive a portion of a roll of strip material therein, a rotatable roller carried by said frame for bearing against the inner portion of a roll of material, said roller being removable from said frame while the roll of material is supported therein, a supporting bearing carried by said frame in a plane below said roller for engaging the outer surface of a roll of material, and a 30 tension arm engaging the roll of material adjacent said roller.

In witness whereof, I have hereunto signed my name this 10th day of January, 1923.

A. NORMAN PAFF.
